AGITATOR FOR WASHING MACHINES

Jabez Curry Nelson, Syracuse, N. Y., assignor to
 Easy Washing Machine Corporation, Syracuse,
 N. Y., a corporation of Delaware

Application November 15, 1935, Serial No. 49,985

6 Claims. (Cl. 68—134)

My invention relates to washing machines and more particularly to a novel agitator or dolly therefor.

An object of my invention is to provide an agitator for a washing machine which is adapted to cleanse the clothes thoroughly in a minimum length of time.

A further object of my invention is to provide an agitator adapted to be mounted for operation in a vat containing clothes and washing fluid, the agitator comprising a multisided closed figure.

Another object of my invention is to provide an agitator for a washing machine adapted to be mounted for operation in a vat containing clothes and washing fluid, the agitator comprising a polyhedrally shaped structure having means mounted thereon for causing agitation of the clothes and washing fluid and a scrubbing action upon the clothes.

More specifically, my invention contemplates the provision of an agitator for a washing machine adapted to be mounted for operation in a vat containing clothes and washing fluid in which the agitator is generally cubical in shape and is provided with means for agitating the clothes and washing fluid and means for exerting a scrubbing and thread-deforming action upon the clothes.

Other objects and advantages of my invention will be more apparent from the following description when taken in connection with the accompanying drawings, in which:

Figure 1 is a view showing the agitator in side elevation mounted in a washing vat.

Figure 2 is a view taken on the line 2—2 of Figure 1.

Figure 3 is a view taken on the line 3—3 of Figure 1.

Figure 4 is a view taken on the line 4—4 of Figure 1.

Figure 5 is a view showing a side elevation of a modified form of my novel agitator mounted in a washing vat.

Figure 6 is a view taken on the line 6—6 of Figure 5.

Figure 7 is a view taken on the line 7—7 of Figure 5.

Figure 8 is a view showing a side elevation of another modified form of my novel agitator mounted in a washing vat.

Figure 9 is a view taken on the line 9—9 of Figure 8.

Figure 10 is a view taken on the line 10—10 of Figure 9.

The agitator of my invention is adapted to be

mounted in a vat or tub 11 in which the clothes and washing fluid are placed. The washing vat may be of any desired shape, either square or circular in cross section. The agitator, generally indicated by the numeral 12, is preferably mounted centrally of the vat 11 and is driven by a shaft 13 extending upwardly through the bottom of the vat. The shaft 13, while it may be rotated, is preferably oscillated by any suitable mechanism and from any suitable source of power, not necessary to be shown or described here-in since such driving mechanism is well known in the art to which this invention applies. Preferably, the shaft is driven in an oscillatory manner so as to drive the agitator through an arc of 180 degrees, more or less, and at a speed of between fifty and sixty oscillations per minute.

The upper end of the shaft is splined, as indicated at 14, to receive cooperating splines 15 formed in a collar 16. The collar 16 is press fitted into a sleeve 17 which surrounds the shaft and extends to the bottom of the agitator at which point it may be slightly enlarged to provide a bearing surface adapted to snugly fit the shaft so as to support the agitator.

The agitator 12 comprises a preferably circular base 18 upon which the agitator proper is mounted. The main portion of the agitator of my invention, broadly considered, is a polyhedron 30 which is a multisided figure bounded by plane faces. While the faces of the polyhedron are preferably plane surfaces, it may be desirable to concave or convex them slightly, in which event the structure will not be truly polyhedral in shape.

I have found that the best form of polyhedron for use as an agitator for washing clothes is a polyhedron whose apices lie on a sphere. I have also found that such a polyhedron should be preferably in the form of a cube as in a cube the faces are at sharp angles with respect to each other whereby the meeting edges exert a substantial scrubbing action on the clothes when the agitator is oscillated.

The cube is preferably mounted on the base 18 so that one of the diagonals through the cube extends in a vertical direction but at an angle to the vertical. Preferably, also, the axis of the agitator forms an acute angle with said one of the diagonals, so that the corners of the cube lie in different horizontal planes. The lower vertex of the cube is cut off, the plane of the cut off portion being perpendicular to the axis of the agitator and the cube is seated on

the base on this flattened portion. The drive shaft 13 and its surrounding sleeve 17 project through the top face 25 of the agitator as indicated at 29'. Upon each of the faces 19, 20, 5 21 and 22, are mounted a pair of small blades or ribs 23 and 24. The ribs 23 are preferably mounted substantially centrally of the faces 19, 20, 21 and 22 while the ribs 24 are preferably mounted just slightly inwardly from one edge of 10 each of the faces 19, 20, 21 and 22 of the agitator and near the corresponding edge of the respective faces. The ends of the ribs are preferably rounded off as shown in the drawings to avoid the formation of sharp corners which are likely 15 to tear the clothes.

15 A blade 26 is provided by extending the face 20 downwardly until it meets the base which forms with the base and the bottom surface of the cube a pocket facing in the clockwise direction. A second but smaller blade 27 extends from 20 the meeting edge of the face 19 and the bottom face to the disk so as to prevent the clothes from being caught between the bottom of the cube and the disk.

25 When the agitator is oscillated, the clothes and washing fluid are violently agitated and whipped back and forth in accordance with the oscillations of the agitator. At the same time, there is a resultant circulation of the clothes 30 and washing fluid around the vat in a clockwise direction. This one-way rotation is caused probably by two factors. First, the blade 26 forms a pocket between the bottom face of the agitator and the base 18 facing in the clockwise direction which exerts a greater thrust on the 35 clothes and washing fluid when the agitator is rotated in the clockwise direction than when it is rotated in the counter-clockwise direction. Second, while the blades 23 exert substantially 40 the same thrust in each direction of rotation of the agitator, the blades 24, by reason of their being placed in a corresponding position on each face of the agitator just inwardly from the meeting edges of the faces, tend to have less effect 45 when the agitator is rotated in the counter-clockwise direction than when it is rotated in the clockwise direction. Of particular importance in the action of the agitator is the fact that each of the four upper corners of the cube lies in a different horizontal plane. The corners, 50 to a certain extent, catch on the clothes and drag them through the body of clothes and since each of the corners lies at a different level, this action is secured throughout the depth of the 55 upper portion of the cleansing fluid.

55 In Figures 5 to 7, inclusive, I have shown an agitator which, while essentially the same as that above described, has been modified in certain important respects. In this modified form 60 of my invention the cube has been mounted on the base 18 with a diagonal thereof vertical, that is, said diagonal lies on the axis about which the agitator is operated. Both the upper and lower vertices are cut off as indicated at 29 to provide 65 flattened portions at both the top and bottom of the cube. A small scrubbing blade 31 of a length about half the width of the faces is mounted in the center of each face 30 and each of the faces is extended at one side beyond the 70 plane of the adjacent face to form blades 32. A cap 33, held in position by a screw 34 is mounted on the top of the cube.

75 In operation, this modified agitator acts essentially the same as the agitator of Figures 1 to 4, inclusive, except that the action is less

turbulent due, probably, to the absence of the agitating blade and due to the symmetrical mounting of the cube with respect to the axis of operation. Due to the fact that the blades 5 32 are each formed by extending each face of the cube beyond the plane of the adjacent face at an edge such that the slight pockets formed face in a clockwise direction, the agitator has a 10 tendency to circulate the clothes in a clockwise direction around the vat.

15 The agitator of Figures 8 to 10 is substantially cubical and also has the cube mounted on the base so that the agitator is oscillated about a diagonal of the cube. If desired, in this construction, the central sleeve may be omitted and 20 a portion 38, integral with the cube, formed to receive the pressed-in collar 16 to which the shaft is splined. Also, the bottom of the cube may be formed in with an enlarged part 39 engaging the shaft to support the cube in position. In this construction, each of the faces 35 25 of the cube are dished or concave, as shown more clearly in Figure 10, so that the angles formed between adjacent faces are acute. The dishing of the faces of the cube causes this agitator structure to exert the desired turbulent effect 30 on the clothes and washing fluid without the use of scrubbing blades.

35 The agitator of this modification is provided with three agitating blades 36. Each of the 30 blades extends from the cube to the base and is the extension of a face of the agitator. Each of the blades near the cube is decreased in width, as at 36', and extends around the corner of the respective face, as at 37, and upwardly along the 35 adjacent edge gradually decreasing in width towards the upper end. These blades, because of their position with respect to the base and the faces of the cube, tend to exert a greater propelling effect on the clothes and washing fluid 40 when the agitator is rotating in a clockwise direction than when it is rotating in the opposite direction. This causes the clothes to change their relative position in the vat whereby different articles of clothing are constantly being presented 45 to the action of the agitator.

50 It will be apparent that I have provided a novel agitator construction and that various modifications may be made in the form of the agitator proper and in the form and relation appurtenances thereto without departing from the spirit of the appended claims.

I claim:

1. In a washing machine of the submerged oscillating agitator type having a vat for containing washing fluid and clothes to be washed, an agitator having a parallelepipedal portion, and an axis of oscillation extending substantially between two apices of the parallelepipedal portion and in a substantially vertical direction. 55

2. In a washing machine of the submerged oscillating agitator type having a vat for containing washing fluid and clothes to be washed, a parallelepipedal agitator having an axis of oscillation extending substantially between two 65 apices of the parallelepiped so as to expose the edges of the agitator to direct contact with the clothes and washing fluid. 60

3. In a washing machine of the submerged oscillating agitator type, having a vat for containing washing fluid and clothes to be washed, a polyhedral agitator having an axis of oscillation extending substantially between the vertices of two opposite dihedral angles. 70

4. In a washing machine of the submerged 75

oscillating agitator type having a vat for containing washing fluid and clothes to be washed, an agitator being a polyhedron in shape wherein the apices of said polyhedron lie substantially on the surface of a sphere, said agitator having an axis of oscillation parallel to a line extending substantially between two non-adjacent apices of the polyhedron, the agitator being so disposed on the axis as to expose the edges of said polyhedron to direct contact with the clothes and washing fluid.

5. In a washing machine of the submerged oscillating agitator type having a vat for containing washing fluid and clothes to be washed, an agitator having the form of a parallelepiped, said agitator being so constructed and arranged that the parallelepiped itself constitutes the main water and clothes agitating influence and said

parallelepiped being mounted in the vat so that at least one of the apices of the parallelepiped is located at a height with respect to the bottom of the vat intermediate the height of the lowest and highest apices.

6. In a washing machine of the submerged oscillating agitator type having a vat for containing washing fluid and clothes to be washed, an agitator comprising a base, a parallelepiped mounted thereon, said agitator being so constructed and arranged that the parallelepiped itself constitutes the main water and clothes agitating part of the agitator and said parallelepiped being mounted on the base so that at least one of the apices of said parallelepiped is located at a height with respect to the base intermediate the height of the lowest and highest apices.

JABEZ CURRY NELSON.
